UNITED STATES PATENT OFFICE.

FRED N. REYNOLDS, OF INDIANAPOLIS, INDIANA.

TACK PULLER, SETTER, AND DRIVER.

1,280,549.

Specification of Letters Patent.

Patented Oct. 1, 1918.

Application filed December 30, 1916. Serial No. 139,939.

To all whom it may concern:

Be it known that I, FRED N. REYNOLDS, a citizen of the United States, residing at Indianapolis, in the county of Marion and

5 State of Indiana, have invented a new and useful Tack Puller, Setter, and Driver, of which the following is a specification, reference being had to the accompanying drawings and to the letters and figures of refer-

10 ence marked thereon.

This invention relates to an implement that is designed to be used for driving tacks in an expeditious manner and has reference more particularly to a device that is adapted for pulling a tack and then holding it for re-setting the tack where it may be desired to drive it, the device being adapted for subsequently driving the tack into place.

An object of the invention is to provide 20 a tool that shall be so constructed as to be able to hold a tack and be used to quickly set the tack into place to be later driven in where required. Another object is to provide a unitary tack puller, setter and driver 25 that shall be especially useful to railway employees or others who are required to secure printed cards or sheets of paper to the sides of cars or other objects. It being a common practice to tear off cards or paper signs 30 from cars when no longer needed and leaving the fastening tacks remain in the wooden sides of the cars, an object of the invention is to save the expense of tacks for securing new cards to the cars by providing 35 means whereby the old tacks may be expeditiously and economically utilized repeatedly.

With the above-mentioned and other objects in view the invention consists in a combination tool that is qualified for drawing a tack and lifting it from place and also holding the tack in convenient arrangement to be reset for driving, the tool being adapted also for firmly setting the tack and for subsequently driving the tack in a convenient 45 manner, the tool being adapted to be operated and controlled by one hand of the workman so as to leave his remaining hand free for handling and placing the card or 50 other article required to be fastened into

place. The invention consists also further in the novel devices and arrangement thereof as herein particularly described and further defined in the appended claims.

Referring to the drawings,—Figure 1 is 55 a fragmentary elevation of a board, as one from a freight car siding, with a number of tacks therein, the tool being applied as being ready for drawing one of the tacks; Fig. 2 is a fragmentary section of the board 60 showing a tack therein and the tool applied in readiness for pulling the tack; Fig. 3 is a fragmentary section of the board and a card on its face to be fastened by the tacks, the tool being shown with a tack held there- 65 in as when carried by the tool to the card to be set for driving; Fig. 4 is a fragmentary section of the board and the card with a tack partly driven therein and the tool arranged approximately in the position in 70 which it would appear at the moment the tack is struck thereby; Fig. 5 is a fragmentary section on the line V—V on Fig. 1; Fig. 6 is a fragmentary section of the tool on the line VI—VI on Fig. 3; Fig. 7 is a 75 plan view of the working side of the tool minus its handle; and, Fig. 8 is a section on the line VIII—VIII on Fig. 7 and a fragmentary section of the board and card in which a tack appears as when being set by 80 the tool to be later driven home.

Similar reference characters throughout the drawings indicate corresponding elements or features of construction herein referred to.

In carrying out the objects of the invention the instrument preferably is composed of a single piece of metal, preferably of steel, and for the purposes of the description is thus referred to. Since the tool is 90 designed more particularly for drawing and replacing tacks found in the vertical sides of cars the invention is described accordingly although not limited to such conditions.

In the drawings the numeral 1 indicates 95 a board or upright object into which tacks 2 may be driven or may be found to have been previously driven, numerous other tacks 2 always being found in the sides of 100

all excepting entirely new cars and therefore the workman need not be hindered with a large supply of tacks for securing cards 3 required on the cars for various purposes, 5 as will be understood.

The tool comprises a solid head 4 that is approximately wedge-shaped and having ample bulk and weight for the purpose required, that side portion 5 of the head which 10 is facing the operator in use being approximately straight, the rear portion 6 of the head being conveniently curved, and a thin handle extends from the head which comprises a shank portion 7 that extends from 15 the rear or thicker portion approximately in alinement with the face 5 and is curved backward, a slightly curved handle portion 8 extending from the portion 7. The curvature of the handle is such as to permit the 20 use of the large face 5 of the head in some cases as a hammer face especially during twilight or by lamp-light when a tack is not clearly visible, the face being sufficiently large for flattening operations. The two 25 sides 9 and 10 of the head preferably are flat and are at right angles to the face 5. The opposite or working portion of the head has a relatively small hammer face 11 that extends from the rear end 6 and on a plane 30 convergently to the face 5 toward the nose of the head. The tool has a working face 12 extending obtusely from the hammer face 11 toward the working end or nose of the head. The working end has a slot 13 that 35 extends from the nose a suitable distance backward toward the plane of the hammer face 11 so as to leave a pulling claw, the planes of the slot and the face being relatively oblique angled, the slot extending 40 across from one to the other of the sides 9 and 10. The claw has a slot 14 of uniform width therein so as to form two claw fingers 15 and 16 that extend forward farther than the nose 17 of the head to be forced 45 under the tack head in sight of the operator when pulling a tack. The nose portion of the head has a hammer face 18 in the slot 13 that faces toward the pulling claw to engage the front of the tack head when setting 50 the tack.

In practical use the tool is placed approximately as shown in Figs. 1 and 2 with the points of the claw fingers 15 and 16 under the head of a tack 2, the working face 12 of 55 the claw being in contact with the board 1 so that the operator may push the head forward and use the claw as a lever whereby to draw the tack, the angle at the junction of the faces 11 and 12 affording a fulcrum, 60 the operator pushing the tool forward as the tack is drawn out so as to catch the tack with its body in the slot 14 and the head of the tack in the slot 13 in which position the tool carries the tack ready for resetting.

The operator places the card or article to be 65 fastened in proper position and swings the tool as a hammer to bring the point of the tack to the proper place, the tack being driven partially into the board by means of the hammer face 18 after which the tool is 70 permitted to descend from connection with the tack and immediately operated as a hammer, striking the head of the tack with the hammer face 11, all being accomplished without the operator being required to turn 75 the tool in his hand or twist his wrist or arm to any uncomfortable position during the operations. The operator may carry a few new tacks for emergency or may quite conveniently draw a few tacks from old cars 80 for emergency use but will usually find an ample supply of previously applied tacks in the sides of cars.

Having thus described the invention, what is claimed as new is—

1. An implement comprising a metallic head that has a greater dimension in length than in width and is relatively thicker adjacent to one end than at the opposite end of the head, said opposite end constituting the forward portion of the head and having a long slot extending from one of the narrower and longer sides of the head adjacent to said end and at an acute angle to said side, the metal of the head on the opposite side of the slot constituting a claw and having a long tack-guiding slot therein, the head having a flat face on the opposite one of its narrower sides that is relatively shorter than the other narrower side and is arranged back of the claw at an obtuse angle thereto, the claw being on an acute angle relatively to the said longer side of the head, and a handle extending from the thicker end portion of the head, whereby 105 to draw a tack and re-set it and also drive the tack without turning the implement, about in the several operations.

2. An implement of the character described, comprising a solid metallic head 110 that has a greater dimension in length than in width and also in thickness and relatively thicker adjacent to one end than at the opposite end of the head, said opposite end constituting a nose portion or front end 115 of the head, said head having a long face on one of its narrower sides and a slot extending from said long face adjacent to said front end at an acute angle to the face, the metal of the head on the opposite side of the 120 slot constituting a claw in which is a long tack-guiding slot, said head having a flat face on the opposite one of its narrower sides that is relatively shorter than said long face and extends back from said claw 125 at an obtuse angle thereto, said claw being on an acute angle relatively to said long face, the rear end of said head being curved

on its narrower side, and a handle that is relatively thinner than said head and comprising a shank portion that extends from said rear end with its front on the plane of said long face, said handle being curved and extending back from said plane and toward the plane of said shorter flat face.

In testimony whereof I affix my signature in presence of two witnesses.

FRED. N. REYNOLDS.
